Inventor,

Luke H. Callan,

By Thomas A. Jenkins Jr.

Attorney,

UNITED STATES PATENT OFFICE.

LUKE H. CALLAN, OF BRISTOL, RHODE ISLAND.

ROAD.

Application filed February 26, 1925. Serial No. 11,823.

My invention relates to roads, especially roads having an exposed surface comprising a layer of paving blocks, and the process of laying the same.

The main object of my invention is to provide a road easy to lay, easy to repair, having parts which may be readily taken up to permit repairs by public utilities for sewers, gas pipes, etc. and which will remain set during extreme variations of temperature and weather. I preferably construct the paving blocks of hard vulcanized rubber. I am aware that rubber has been used for the exposed surface of road beds and am also aware that rubber tiles or blocks have also been used both for floors and for the exposed surfaces of road beds but so far as I am aware no satisfactory road has yet been built wherein the exposed layer comprises a plurality of hard rubber vulcanized paving blocks which will remain set during the expansion and contraction which takes place during the year.

My invention comprises a road consisting of a base of cement or wood, a layer of a binder laid thereon and a plurality of paving blocks preferably of hard vulcanized rubber laid thereon in loosely spaced interlocked relationship peculiarly adapted for use where the road base is made of grouting or other plastic material which expands or contracts with changes in temperature. The temperature has no appreciable effect on hard vulcanized rubber paving blocks and no one has heretofore provided vulcanized rubber paving blocks so constructed as to permit relative contraction and expansion of the road base. Where a rubber sheet is employed as the exposed surface of a road bed or where tiles firmly united to other tiles have been employed, in the summer months said surfaces are apt to crack due to the expansion thereof and in winter months are apt to bulge due to the contraction thereof. The advantages of a road bed having the wearing qualities of a surface of hard rubber are well known as it lasts a very long time and will stand much rough traffic without even showing it.

A further object of my invention is to provide as a new article of manufacture an improved hard vulcanized rubber paving block. I am aware that hard vulcanized rubber paving blocks comprising blocks or tiles having projections therefrom are old. These may be divided into two classes, firstly those having projections extending into the road

base usually of dove-tail shape which permit no relative expansion and contraction between the rubber blocks and the road base and secondly those which have projections on their sides or ends or both adapted to register in complementary recesses on the sides or ends of adjacent blocks for various purposes. So far as I am aware, however, all blocks of this type have been adapted to be firmly secured to the adjacent blocks in one fashion or another either by nails or by having protuberances extending therefrom adapted to firmly secure them in unspaced relationship to adjacent blocks. It is obvious that any type of blocks which are firmly secured either to the road base or to the adjacent blocks, will crack or get out of alignment and bulge with variations in temperature.

My invention comprises paving blocks having means thereon adapted to cooperate with complementary means on adjacent blocks to permit expansion of the road base without getting said blocks out of alignment and to permit contraction of said base without causing said blocks to bulge. Specifically this means comprises comparatively weak projections on one end and one side of said blocks preferably adjacent to the base thereon adapted to project into complementary recesses, preferably adjacent to the base on adjacent blocks, said projections being of a substantially greater length than the length of said recess but of substantially lesser width. As the projections are of a substantially less width than the recesses it is obvious that said base may expand and also move the blocks without getting said blocks out of alignment by the narrower projections moving relatively in the wider recesses of adjacent blocks. As the road base contracts it is obvious that it will cause relative movement between the individual blocks. As the projections are as stated comparatively weak, under the great force of this contraction they will merely bend over or spread out in the larger recesses made therefore in the adjacent blocks, however, without causing the blocks to bulge. Even after this contraction has once taken place, however, the projections will still be of such a length as to prevent the blocks from getting out of alignment on later expansion of the base.

In addition I provide the base of the blocks with cushioning recesses which so far as I am aware are new in blocks or tiles of any type. These perform three functions, they

serve to receive some of the binder therein which tends to prevent relative movement between the blocks and base, they serve to give a springiness or cushioning effect to the upper surface, air being more easily compressed than rubber, and as a partial vacuum may be formed therein they tend to provide suction means to permit the atmospheric pressure to further assist in binding the blocks to the base.

In addition, I provide means on the exposed surface thereof to provide a gripping surface for traffic which so far as I am aware is new in blocks of this description. In my preferred embodiment said means comprises diagonal corrugations which provide a gripping surface effective in every direction.

A further object of my invention is to provide an improved method of laying roads of this description. For this purpose I provide a cement binder which preferably comprises approximately 75% of coal-tar and 25% of rubber cement which firmly binds the blocks to the base, yet permits the necessary relative movement thereof.

These and such other objects of my invention as may hereinafter appear will be best understood from a description of the accompanying drawings which illustrate various embodiments of my invention.

In the drawings, Fig. 1 is a plan view partially broken away, of a road constructed in accordance with my invention, the paving blocks being in spaced relationship as laid.

Fig. 2 is a plan view similar to Fig. 1 showing the position the blocks assume after expansion and contraction of the base.

Fig. 3 is a transverse sectional view of a road constructed in accordance with my invention.

Fig. 4 is an enlarged transverse sectional view taken along the line 4—4 of Fig. 1.

Fig. 5 is a longitudinal sectional view taken along the line 5—5 of Fig. 4.

Fig. 6 is an inverted plan view of the blocks as laid taken along the line 6—6 of Fig. 4.

Fig. 7 is an inverted plan view of the blocks similar to Fig. 6, on a portion of the road surface wherein the base has contracted to bend over the projections in the recesses of the blocks.

Fig. 8 is a perspective view of an individual block.

Fig. 9 is an inverted perspective view of an individual block.

Fig. 10 is a transverse sectional view similar to Fig. 4 showing a modified form of my invention having a cushioning layer of bituminous material between the base and the binder.

In the drawings, wherein like characters of reference indicate like parts throughout, 20 generally indicates a paving block constructed in accordance with my invention.

Said blocks are preferably of oblong shape or rectangular parallelepipeds and as stated are preferably constructed of hard vulcanized rubber. The desirability of paving blocks constructed of hard vulcanized rubber has already been referred to. Said paving blocks are provided on one side and preferably also on one end thereof with comparatively weak projections 22, preferably also of oblong shape. Said blocks are provided on the opposite side and opposite end from said projections 22 with the oblong recesses 24. The projections 22, to space the blocks from each other, are of substantially greater length than the length of said recesses but are of a substantially lesser width. The blocks 20 are also preferably provided with the cushioning recesses 26 preferably rectangular or of a diamond shape on the base thereof. Said paving blocks are also preferably provided with means to provide a gripping surface on the upper surface thereof for traffic which in my preferred embodiment preferably comprise diagonally corrugated recesses 28.

As stated, my invention comprises a new type of road preferably employing as component parts thereof the paving blocks described in the preceding paragraph. Said road is provided with the base 30. While any suitable type of road base may be employed, I preferably employ a base of a plastic material although wood or any of the other types of road bases may be employed. In the preferred embodiment shown said road base 30 comprises a grouting composed of the usual trap rock 32 joined together by the usual cementitious binder 34. In the modification shown in Fig. 10, I further cover this layer of grouting with an additional cushioning layer 36 of bituminous material preferably mixed with sand as is usual in road bases of this type, though the road may be constructed with or without this additional layer as desired. This cushioning layer 36 is preferably used on old roads to smooth off the old often rough surface thereof and to provide a flat surface for the laying of the binder and the blocks thereon. In new roads where the base is laid flat, though sometimes desirable it is not necessary. As explained, especially where the road base is constructed of a plastic or cementitious material it is apt to expand and contract with changes in temperature.

To more securely bind the blocks to the base, I cover said base 30 or bituminous layer 36 where it is employed with a layer of a binder 40. I preferably employ a binder 40 I have designed for this purpose, which comprises substantially 75% coal-tar and 25% of rubber cement. To provide an irregular surface for the binder 40 to act upon I preferably roughen or indent the upper surface of the grouting 30 or bituminous layer 36,

as at 38. This may be done by a grouting roller or in any suitable manner.

After the layer of binder 40 has been applied to the upper roughened surface of the base, I preferably lay the blocks 20 thereon in spaced loosely interlocked relationship. It is obvious that the blocks may be readily laid, the projections 22 thereof being readily fitted into the complementary recesses 24 in the ends and sides of adjacent blocks already laid. It is also obvious that when for any reason it is desired to take up a portion of said road bed, any individual block 20 may be readily raised right up, the projections 22 thereof being readily pulled out of the complementary recesses 24 of adjacent blocks if the block 20 is grasped at the proper corner.

When the road 50 is laid it is obvious that if desired the spaces 42 between the blocks may be filled with sand 44 or any other suitable filler and it then comprises a base 30 preferably constructed of a plastic material which expands and contracts with changes in temperature, which base 30 preferably comprises a layer of grouting and a cushioning layer of bituminous material 36 laid thereon, having a roughened upper surface 38, a layer of a composition coal-tar and cement binder 40 on the upper surface thereof and a layer of hard vulcanized rubber paving blocks 20 laid thereon in spaced loosely interlocked relationship having the comparatively weak projections 22 on the ends and sides thereof adapted to project into the complementary recesses 24 on adjacent blocks 20; said projections 22 being of a substantially greater length than the length of the recesses 24 but of a substantially lesser width whereby said base 30 may expand without getting said blocks 20 out of alignment (as shown in Fig. 2) and on contraction of said base 30, the said projections 24 may be bent without causing said blocks 20 to bulge and cushioning recesses 26 on the base of the blocks to receive the binder 40 therein to provide a better binding surface, to add springiness to the road and to aid in pneumatically binding the blocks 20 to the base 30 and sand 44 in the spaces 42 between the adjacent blocks, said blocks 20 having means preferably comprising the diagonal recesses 28 on the upper surface thereof to provide a gripping surface for traffic. It is obvious that each part of this road combines with the other parts in a new manner to form a new structure, resistant to the elements, of the base 30 functioning in the usual way, the layer 40 of binder functioning to firmly yet yieldingly bind the blocks 20 to the base 30, the cushioning recesses 28 aiding in this purpose and the blocks 20 themselves forming a durable traffic surface provided with specific means for gripping the traffic and said blocks being provided with means thereon adapted to co-operate with complementary means on adjacent blocks to space the blocks and to

permit expansion of said base without getting said blocks out of alignment and to permit contraction of said base without causing said blocks to bulge, a construction hitherto desired in roads constructed with a rubber surface, resistant to wear and capable of standing extreme variations in temperature.

When the base 30 contracts in cold weather, assuming that the contraction takes place around the point X in Fig. 2, it is obvious that the sand 44 in the spaces between the blocks will be readily forced out as the blocks move nearer to each other as shown in Fig. 2, and that under the great pressure the comparatively weak projections 22 will bend over or spread out within the comparatively wider recesses 24 as shown in Fig. 7, thus permitting the blocks to move closer during contraction of the road bed without bulging. It is also obvious that as the blocks adjacent to the contraction centre X move nearer to each other, the blocks further away from it will spread apart as shown in Fig. 2. The projections 22 even if bent up as shown in Fig. 7 will still register within the recesses 24 and the recesses 24 being of a greater width than the projections 22 will permit said blocks 20 to again spread apart from each other without getting out of alignment.

Though I preferably employ hard rubber, and preferably hard rubber which has been vulcanized, it is obvious that hard rubber in any form may be employed or that equivalent materials, which will permit the projections to bend and the recesses 26 to function as such, may be employed.

In the claims I employ the word "sides" in reference to said blocks in referring either to the sides or ends of said blocks or both.

It is understood that my invention is not limited to the specific embodiments shown or processes described and that various deviations may be made therefrom without departing from the spirit and scope of the appended claims.

What I claim as new and desire to secure as Letters Patent is:

1. A road comprising a plastic base, comprising a layer of grouting and a cushioning layer of bituminous material laid thereon having a roughened upper surface, a layer of composition coal-tar and rubber cement binder on the upper surface thereof, a layer of hard rubber paving blocks laid thereon in spaced loosely interlocked relationship having comparatively weak projections on the ends and sides thereof adapted to project into complementary recesses on the ends and sides of adjacent blocks, said projections being of a substantially greater length than the length of said recesses but of a substantially lesser width, whereby said blocks may be spaced by said projections under ordinary traffic and climatic conditions and, under extreme temperatures, said base may expand without get-

ting said blocks out of alignment and on contraction thereof said projections may bend without bulging said blocks and cushioning recesses on the base thereof to receive the binder and to aid in pneumatically binding said blocks to the base and sand in the spaces between said blocks.

2. A road comprising a base, a layer of binder on the upper surface thereof and a layer of hard rubber paving blocks laid thereon in spaced loosely interlocked relationship having comparatively weak projections on the ends and sides thereof adapted to project into complementary recesses on the ends and sides of adjacent blocks, said projections being of a substantially greater length than the length of said recesses but of a substantially lesser width, whereby said blocks may be spaced by said projections under ordinary traffic and climatic conditions and, under extreme temperatures, said base may expand without getting said blocks out of alignment and on contraction thereof said projections may bend without bulging said blocks.

25. 3. A road comprising a base, a layer of composition coal-tar and rubber cement binder on the upper surface thereof, and a layer of hard rubber paving blocks laid thereon in spaced loosely interlocked relationship having comparatively weak projections on the ends and sides thereof adapted to project into complementary recesses on the ends and sides of adjacent blocks, said projections being of a substantially greater length than the length of said recesses but of a substantially lesser width, whereby said blocks may be spaced by said projections under ordinary traffic and climatic conditions and, under extreme temperatures, said base may expand without getting said blocks out of alignment and on contraction thereof said projections may bend without bulging said blocks.

4. A road comprising a relatively expandable and contractible base, a layer of binder on the upper surface thereof, and a layer of hard rubber paving blocks laid thereon in spaced loosely interlocked relationship having comparatively weak projections on the ends and sides thereof adapted to project into complementary recesses on the ends and sides of adjacent blocks, said projections being of a substantially greater length than the length of said recesses but of a substantially lesser width, whereby said blocks may be spaced by said projections under ordinary traffic and climatic conditions and, under extreme temperatures, said base may expand without getting said blocks out of alignment and on contraction thereof said projections may bend without bulging said blocks, and cushioning recesses on the base thereof to receive the binder and to aid in pneumatically binding the blocks to said base.

5. A road comprising a base, a layer of

composition coal-tar and rubber cement binder on the upper surface thereof, and a layer of hard rubber paving blocks laid thereon in spaced interlocked relationship, said blocks having means thereon adapted to cooperate with complementary means on adjacent blocks to space said blocks and to permit expansion of said base without said blocks getting out of alignment and to permit contraction of said base without bulging said blocks.

6. A road comprising a base, a layer of binder on the upper surface thereof, a layer of hard rubber paving blocks laid thereon in spaced interlocked relationship, said blocks having means thereon adapted to cooperate with complementary means on adjacent blocks to space said blocks and to permit expansion of said base without said blocks getting out of alignment and to permit contraction of said base without bulging said blocks and cushioning recesses on the base thereof to receive said binder and to aid in pneumatically binding said blocks to said base.

7. A road comprising a relatively expandable and contractible base, a layer of binder on the upper surface thereof, and a layer of hard rubber paving blocks laid thereon in spaced interlocked relationship, said blocks having means thereon adapted to cooperate with complementary means on adjacent blocks to space said blocks and to permit expansion of said base without said blocks getting out of alignment and to permit contraction of said base without bulging said blocks.

8. As a new article of manufacture, a hard rubber paving block having comparatively weak projections on one side and recesses on the opposite side thereof, said projections being of a substantially greater length than the length of said recesses but of a substantially lesser width.

9. The claim according to claim 8 in which the projections and recesses are located adjacent the base thereof.

10. The claim according to claim 8 in which the block is provided with cushioning recesses on the base thereof.

11. As a new article of manufacture a hard rubber paving block having comparatively weak projections on one side and end thereof and recesses on the opposite side and end thereof, said projections being of substantially greater length than the length of said recesses but of a substantially lesser width.

12. The claim according to claim 11 in which the projections and recesses are located adjacent the base of the block.

13. The claim according to claim 11 in which the block is provided with cushioning recesses on the base thereof.

In testimony whereof I affix my signature.

LUKE H. CALLAN.
